UNITED STATES PATENT OFFICE

OTTO MOOG, OF BRUNSWICK, GERMANY

ROLLER GRINDING MILL

Application filed November 30, 1928, Serial No. 322,883, and in Germany December 19, 1927.

My invention relates to improvements in roller grinding mills, and more particularly to the mechanism for regulating the feed of grain or other substance to the rollers thereof. In order to obtain high efficiency in roller grinding mills it is necessary to maintain the grain or other substance to be ground in the container provided above the feeding mechanism of the mill as far as possible at the same level. The object of the improvements is to provide an apparatus which is simple in construction and effective in operation, and with this object in view my invention consists in providing a floating member within the said container, which exactly follows any change of the level of the material within the container. Another object of the improvements is to provide a relay or servo-motor in connection with the said floating member for controlling the supply of grain from the container to the rollers.

With these and other objects in view my invention consists in the matters to be described hereinafter and particularly pointed out in the appended claims, reference being had to the accompanying drawings, in which the same letters of reference have been used to indicate corresponding parts.

In said drawings,

Fig. 1, is an elevation partly in section showing a two roller mill,

Fig. 2, is a top plan view of Fig. 1,

Fig. 3, is a sectional elevation on an enlarged scale showing the relay controlling the supply of grain, and

Fig. 4, is a sectional elevation taken on the line 4—4 of Fig. 3.

In the example shown in the drawings the mill comprises a casing 2 provided at its top with a container 4, the said container communicating with the casing 2 through chutes 3. Within the casing 2 there are two pairs of grinding rollers *a*, *a*, one of the pairs of rollers only being shown in Fig. 1. Above the rollers *a* there are two feed rollers *b*, *b* cooperating with a feed plate *d* rockingly mounted on a shaft *c* and adapted to be set relatively to one of the rollers *b* into position for allowing a regulated amount of the material to be ground to pass from the chute

3 to the rollers *a*, *a*, the said amount depending on the size of the gap provided between the plate *d* and the roller *b*.

The shaft *c* extends to the outside of the casing of the mill, and at its outer end it carries a crank *c* connected by a link *e* with a lever *f* rockingly mounted at *g*, the said lever being jointed to a relay or servo-motor. Preferably the link *e* carries a weighted body *t* tending to draw the link downwardly and to rock the plate *d* towards the roller *b* for reducing the area of the gap provided between the said plate and roller.

The said servo-motor is constructed as follows:

Beside the top part of the casing 2 a container *r* is mounted, which is illustrated in detail in Figs. 3 and 4. Within the container *r* there is a cylinder *v* having a piston *h* reciprocating therein. The piston rod *h* of the piston is connected with the bifurcated outer end of the lever *f*. Thus the position of the plate *d* depends on the position of the piston *h* within the cylinder *v*, the area of the gap provided by the plate *d* being increased when the piston is moved downwards.

Within the container *r* there is a certain amount of oil, and the said oil is adapted to be forced into the top part *z* of the cylinder *v* by means of a pump *y* carried by the bottom wall of the cylinder and having its suction pipe *y* near the bottom of the container *r*. In the example shown in Figs. 3 and 4 the said pump consists of a pair of gear wheels *y* rotated at uniform speed by means of a pulley *y*. The pressure duct *y* is connected with the top part *z* of the cylinder *v*.

Within the piston rod *h* a valve stem *w* is guided which controls an orifice *w* communicating with the top part *z* of the cylinder *v* and with the container *r*. Thus, when the valve stem *w* closes the said orifice the oil supplied to the chamber *z* can not escape, and it drives the piston *h* downwardly, thus lifting the plate *d*. The stem *w* is acted upon by a bell crank lever *o* connected with a link *n*, a spring *o* carried by the stem tending to push the bell crank lever *o* into engagement with screw nuts *o*.

The said relay *r* is controlled by a floating

- member disposed within the container u and following the movement of the grain through the said container, the said member moving upwardly when there is no grain within the container, and moving downwardly when the material flows freely through the container. In the example shown in Fig. 1 the said member consists of a spindle i provided with bars i^1 preferably laterally displaced relatively to each other or arranged around the said bar on a helix. The said bars i^1 may be circular in cross-section, or, as shown in the figure, they are roof-shaped. Thus, when the grain flows downwardly through the container u the member i, i^1 is immersed in the grain to a certain depth, and the movement of the bars disposed within the grain is determined by the height of the material passing through the container u . Preferably the bars i^1 are shorter at the bottom part of the member than at the top thereof, so that the downward movement is greater, the fuller the container u . The member i, i^1 controls the said relay, and therefore the position of the plate d , the plate d leaving a large gap when there is much material within the container u and reducing the area of the said gap if the amount of material within the container u is small.
- Instead of the member consisting of the bars i^1 , a disk element having a flat base may be used which floats on or in the material and drops on removal of the material.
- The regulating member i, i^1 is suspended by means of a spring k from an arm l^1 of a rock shaft l , and a crank arm m secured to the shaft l is connected with the link n . If the amount of grain within the container u is reduced, the regulating member i, i^1 rises within the container and by the weight t the mechanism connected with the regulating member is moved, the link n being pulled forwardly in Fig. 2 and lifting the stem w away from the orifice x . Therefore the oil forced into the chamber z of the cylinder is free to escape through the said orifice x and into the bottom part of the container u , so that the piston h is relieved of the pressure of the oil, and it is moved upwardly by the weighted body t , thus rocking the plate d downwardly and reducing the area of the gap. On the other hand, if there is much grain within the container u , the member i, i^1 moves downwardly with the said grain, the link is pushed rearwardly in Fig. 2, and the stem w is placed on its seat, so that the piston h is forced downwardly by the pressure of the oil within the chamber z .
- In order to be able to regulate the velocity with which the piston h sinks, it is advisable to provide an outlet orifice v^1 (Fig. 4) in the cylinder v which is filled with liquid below the piston, variable by means of a screw v^2 , so that it can be made narrower with the

result that escape of the oil from the chamber v is rendered more difficult.

In order to provide definite stable regulation of the feed plate d and to avoid oscillations, the spring k which supports the yielding element or float in the container u , is so dimensioned that every position of the float corresponds to a definite position of the servomotor and feed plate d .

The arrangement described also provides that when the operation of the roller mill is interrupted for any reason the feed plate d closes under the action of a weight or spring owing to the default of the oil pressure and to the flowing out of the oil from the chamber z by reason of leakage due to imperfect fit of the parts, or by way of leak passages provided for that purpose.

The point at which the crank o engages the valve stem w (Fig. 3) is adjustable by means of the nuts o^1 and the transmission of the movement is rendered resilient by means of the spring o^2 .

In order to be able to limit the opening movement of the feed plate d the valve stem is threaded and its upper end which carries an adjustable nut o^3 is extended above a bridge o^4 or other fixed stop. The movement of the stem and accordingly of the servomotor and the feed plate d can be limited by adjusting the nut o^3 , the spring o^2 being compressed on further sinking of the float i .

If adjustment of the feed plate opening is not desired i. e. if the plate is to be secured in any position, this can be effected by clamping the crank o (Fig. 3) to a fixed element o^5 by means of a clamping screw o^6 mounted in a slot o^5 in a sector o^6 connected with the crank o .

Any other liquid or compressed air can of course be used as the driving power for the pump y^1 instead of oil. Any other source of power, for example, electricity or even a purely mechanical servo-motor can be used instead of the hydraulic or pneumatic operation for the servo-motor. The modifications in the device rendered necessary will be obvious to the expert.

By means of my improved apparatus the level of the grain or other substance to be ground within the container u is maintained practically uniform.

While in describing the invention reference has been made to a particular example embodying the same I wish it to be understood that my invention is not limited to the construction shown in the drawings, and that various changes may be made in the general arrangement of the apparatus and the construction of its parts without departing from the invention.

I claim:

1. In a roller grinding mill having grinding rollers, the combination of a container, means for regulating the supply of the ma-

- terial to be ground from said container, power operated means controlling said regulating means, and means controlled by the material within said container for controlling said power operated means.

5. In a roller grinding mill having grinding rollers, the combination of a container, a gate or valve for regulating the supply of material from said container, power operated means operatively connected with said gate or valve, and a yielding device within said container and actuated according to the level of the material therein for controlling said power operated means.

10. In a roller grinding mill having grinding rollers, the combination of a container, means for regulating the supply of the material to be ground from said container, mechanism operated by pressure fluid connected with said regulating means, a pump for supplying pressure fluid to said mechanism, means controlling the flow of the fluid from said pump to said mechanism, and means controlled by the material within said container for operating said controlling means.

15. In a roller grinding mill having grinding rollers, the combination of a container, means for regulating the supply of the material to be ground from said container, a member comprising laterally projecting rods suspended within said container in position for floating within the material contained therein and operatively connected with said regulating means.

20. In a roller grinding mill having grinding rollers, the combination of a container, means for regulating the supply of the material to be ground from said container, a member comprising laterally projecting rods suspended within said container in position for floating within the material contained therein and operatively connected with said regulating means.

25. In a roller grinding mill having grinding rollers, the combination of a container, means for regulating the supply of the material to be ground from said container, and automatic means tending to set said controlling means into position for interrupting the supply of material from said container to said rollers, power operated means controlling said regulating means, and means controlled by the material within said container for controlling said power operated means.

30. In a roller grinding mill having grinding rollers, the combination of a container, means for regulating the supply of the material to be ground from said container, a cylinder and piston connected with said controlling means, a pump for continuously supplying pressure fluid to said cylinder at one side of the piston, the cylinder being provided at the opposite side of the piston with an outlet, means for varying the area of said outlet, a valve permitting the escape of the pressure fluid from said cylinder, and means depending on the level of the material within said container for controlling said valve.

35. In a roller grinding mill having grinding rollers, the combination of a container, means for regulating the supply of the material to be ground from said container, a cylinder, a piston reciprocating therein and a piston rod connected with said regulating means, means for limiting the movement of said piston and rod, a pump for supplying pressure fluid to said cylinder at one side of the piston, and means controlled by the material within said container for controlling the pressure of the fluid within said cylinder.

40. In a roller grinding mill having grinding rollers, the combination of a container, means for regulating the supply of the material to be ground from said container, a member comprising laterally projecting rods suspended within said container in position for floating within the material contained therein and operatively connected with said regulating means, the arms of said member being laterally displaced with relation to one another.

45. In a roller grinding mill having grinding rollers, the combination of a container, means for regulating the supply of the material to be ground from said container, a member comprising laterally projecting rods suspended within said container in position for floating within the material contained therein and operatively connected with said regulating means, said arms being mounted on said member along a helix.

50. In a roller grinding mill having grinding rollers, the combination of a container, means for regulating the supply of the material to be ground from said container, a member comprising laterally projecting rods suspended within said container in position for floating within the material contained therein and operatively connected with said regulating means, said arms being reduced in length from the top part to the bottom part of the member.

55. In a roller grinding mill having grinding rollers, the combination of a container, means for regulating the supply of the material to be ground from said container, a member comprising laterally projecting rods suspended within said container in position for floating within the material contained therein and operatively connected with said regulating means, said rods having roof-shaped cross-sections.

60. In testimony whereof I have affixed my signature.

DR. OTTO MOOG
